ATTORNEY

UNITED STATES PATENT OFFICE

HERMAN KITZE, OF OWEN, WISCONSIN

ROCKING TOY

Application filed June 3, 1929. Serial No. 368,057.

My present invention has reference to a rocker for children, and my object is the provision of a simple, cheaply constructed but strong and efficient device for this purpose in which the improvement is provided with a central seat and with end seats all supported at a suitable elevation above the rocker, and whereby the device may be employed by one, two or three children.

10 A further object is to provide a rocking toy for this purpose in which the seats disposed at the ends thereof are longitudinally adjustable so that they can be occupied by children of different weights without disturbing the equilibrium of the improvement.

To the attainment of the foregoing and many other objects which will present themselves, the improvement further resides in certain other novel features of construction, 20 combination and operative association of parts, one satisfactory embodiment of which is disclosed by the accompanying drawings.

In the drawings:

Figure 1 is a side elevation of my improvement with parts broken away and parts in section.

Figure 2 is a top view thereof.

Figure 3 is an end view thereof.

At disclosed by the drawings I make use of two spaced rockers 1. In constructing the rockers I cut away the upper edges longitudinally from points adjacent to the ends thereof and utilize the strips of the cut away portions for the purpose to be hereinafter described. The upper ends of the rockers are cut straight and have secured thereto spacer boards 2. The boards 2 are nailed to the ends of the rocker. Inward of the said boards 2 the rockers are connected by other transverse boards 3 which are also nailed to the upper edges of the rockers at the depressed portions thereof. The boards 2 have their confronting ends arranged out of contact with each other and there is secured by stove bolts to the confronting ends of the said boards 3 the lower angle ends of upstanding strong metal straps 4. These straps 4 are slightly inclined toward each other to thereby add strength thereto so that they will amply support thereon a seat 5 which is secured by stove bolts to the

upper inwardly directed flange 6 of the said straps 4. For distinction the lower inwardly directed flanges are indicated by the numeral 7. Four straps are employed, the same being arranged in oppositely spaced pairs so that the central seat 5 of the improvement is effectively supported.

Having their angle ends bolted to the upper edge of the rockers 1, directly outward with respect to the boards 3 there are other vertically straight and longer heavy metal straps 8. The lower angle ends of these straps are indicated by the numeral 9. The straps have upper inwardly directed angle ends 10 provided with openings for bolts which pass through transverse connecting bars 11. The bolts 12 which pass through the connecting bars 11 also pass through the longitudinal side rails 13 of the improvement, and these side rails are formed from the cut-away portions of the rockers which may be also true with respect to the transverse spacer and brace bars 11.

Inward of the bars 11 there are bolted to and arranged transversely of the upper side bars 13 other bars 14. Arranged at the center of the device to underlie the bars 14 and to rest on the bars 11 there are strong wooden strips or plates 15, respectively. The bolts 16 which secure the upper transverse bars 14 to the side bars 13, as well as the bolts 12 have their ends, of course, engaged by suitable nuts and the bolts 17 and 18 which pass through the boards or plates 15 and through the center of the transverse bars 14 and 11 have screwed on their lower ends wing nuts 19, respectively. The strips or plates 15 extend a suitable distance beyond the ends of the rockers 1 and the outer portions of these strips or plates 15 are provided with elongated slots 20. Arranged over each of the plates 15 and also disposed over the slots 20 there are wooden seats 21. Passing through the seats 21 there are bolts 22 that have washers 23 thereon, and the said bolts are engaged by wing nuts 24 which compress the washers 23 against the under face of the strips or plates 1. As the bolts 22 pass through the elongated openings 20 it will thus be noted that either of the seats may be ad-

justed toward or away from the uprights or from the frame of the improvement and consequently children of different weights may occupy either of the seats without canting the rockers.

5. There is secured to the forward end of each of the seats the angle ends of upwardly extending metal members 25, the said metal members having their outer or upper ends rounded upon themselves to provide eyes for handles 25 which are to be gripped by the occupants of the seats 21. The occupant of the seat 5 may grip either of the bars 14.

10. The device as will be noted is of an extremely simple construction and may have its wooden parts formed from material which is considered waste in mills. The metal parts of the improvement may be cheaply purchased and may be easily shaped and have their ends readily bent and secured to the wooden parts of the structure. The occupants of the seat rest their feet upon the end boards 2 that connect the rockers 1.

15. The simplicity and advantages of the improvement will, it is thought, be understood and appreciated so that further detailed description will not be required. However, I deem it necessary to add that I do not wish to be restricted to the precise details herein set forth and, therefore, hold myself entitled to make such changes therefrom as fairly fall within the scope of what I claim.

20. Having described the invention, I claim:
35. 1. A child's rocker designed for use by one, two or three children, comprising a pair of spaced rocker members, boards connected to the upper ends of the rockers, other boards connected to the upper edges of the rocker but arranged inwardly of the end boards, a seat centrally supported by and arranged above the last mentioned boards, metal uprights secured to the rockers inward of the end boards and outward of the last mentioned boards, transverse wooden plates connecting the uprights, side rails overlying and secured to the ends of the uprights, transverse plates connecting the side rails, plates underlying the inner transverse plates and overlying the outer transverse plates, arranged at the center thereof and removably secured thereto and said plates extending beyond the ends of the rocker and provided, adjacent to their outer ends with elongated slots and a seat arranged over each of the last mentioned plates having a nut engaged bolt passing therethrough and passing through the slots in said plates, and handles supported by but arranged above the inner ends of the seats.

25. 2. A child's rocker designed for use by one, two or three children, comprising a pair of spaced rocker members, boards connected to the upper ends of the rockers, other boards connected to the upper edges of the rocker but arranged inwardly of the end boards, a seat centrally supported by and arranged

30. above the last mentioned boards, metal uprights secured to the rockers inward of the end boards and outward of the last mentioned boards, transverse wooden plates connecting the uprights, side rails overlying and secured to the ends of the uprights, transverse plates connecting the side rails, plates underlying the inner transverse plates and overlying the outer transverse plates, arranged at the center thereof and removably secured thereto and said plates extending beyond the ends of the rocker and provided, adjacent to their outer ends with elongated slots and a seat arranged over each of the last mentioned plates having a nut engaged bolt passing therethrough and passing through the slots in said plates, and handles supported by but arranged above the inner ends of the seats.

35. 3. A rocker toy of the class described comprising rocker members which have their upper edges cut inwardly and longitudinally from adjacent the ends thereof to provide depressed portions and the upper edges of the rockers above said depressed portions being straight, foot boards secured to the upper edges of the ends of the rockers, other boards secured to the upper edge at the depressed portion of the rockers, metal uprights secured to the last mentioned boards, a seat supported upon the uprights, other metal uprights secured to the upper edge of the rocker outward of the last mentioned boards, transverse strips comprising plates secured to the upper ends of the uprights, longitudinal strips formed from the cut-away portion of the rockers arranged over and secured to the transverse strips, other transverse strips secured to the side rails inward of the first mentioned strips, a wooden plate underlying the last mentioned strips and overlying the first mentioned strips and secured to both of said strips, each of said wooden plates extending beyond the rockers and being provided with elongated slots, a seat overlying each of the plates and covering the slots therethrough, a bolt member passing through each seat and through the slots in the plate, a washer on each bolt, a wing nut engaging the bolt for forcing the washer against the plate, a centrally rounded metal strap having angle depending portions which are secured to the seats adjacent to the inner ends thereof and the rounded portions of the straps providing eyes for handles.

40. In testimony whereof I affix my signature.
HERMAN KITZE.
